Attorneys

UNITED STATES PATENT OFFICE.

ROBERT FRIEDLEY, OF EDMONTON, ALBERTA, CANADA.

ANTISLIPPING DEVICE FOR SKIDS.

Application filed November 9, 1922. Serial No. 599,827.

To all whom it may concern:

Be it known that I, ROBERT FRIEDLEY, a subject of the King of Great Britain, residing at Edmonton, in the Province of 5 Alberta and Dominion of Canada, have invented certain new and useful Improvements in Antislipping Devices for Skids, of which the following is a specification.

This invention relates to improvements in 10 skids to facilitate the handling of timber and the like.

The primary object of this invention is the provision of an improved anti-slipping arrangement for the skids of guide ways, 15 which will facilitate the handling of lumber and other articles upon the skids by reason of calk members which are adapted for engaging the lumber or articles being moved over the skids.

20 A further object of this invention is the provision of an improved anti-slipping device, and retaining means for detachable assemblage to skids, such as logs, whereby an efficient skid may be provided for use 25 in connection with the decking of logs, or for use in connection with the handling of other materials.

30 A further object of this invention is the provision of an improved anti-slipping skid chain embodying a novel assemblage of calked links.

Other objects and advantages of this invention will be apparent during the course 35 of the following detailed description.

35 In the accompanying drawing, forming a part of this specification, and wherein similar reference characters designate corresponding parts throughout the several views,

Figure 1 is a perspective view of a pair 40 of skids embodying the improved anti-slipping devices, showing the skids in the arrangement which they ordinarily assume to facilitate the decking of logs.

Figure 2 is a perspective view of the 45 upper end of the improved anti-slipping device for skids.

Figure 3 is a bottom plan view, partly in section, of a link element embodied in the improved anti-slipping chain.

50 Figure 4 is a side elevation of a link embodied in the improved anti-slipping chain.

Figure 5 is a transverse cross sectional view, taken substantially on the line 5—5 of Figure 3.

55 In the drawing, wherein for the purpose

of illustration is shown but the preferred embodiment of this invention, the letter A generically indicates the manner in which logs or timber is arranged in tiers by means of skids B. In connection with the skids 60 B, novel anti-slip devices C are employed to facilitate the moving of the logs along the skidway, B, said means C preferably being a chain formed of a plurality of novel link members D.

In arranging the logs, lumber jacks resort to the use of skids, which ordinarily comprise two pieces of timber shaped so that the same may be diagonally braced against the upper tier of a pile of timber. 70 Logs are then rolled or drawn over the skids to form succeeding tiers. The operation of sliding or drawings the logs over the skids is not easy. In winter time, when logging is most generally carried on, the 75 skids become slippery, incident to wearing of the bark off the skids and formation of ice. It can thus be readily understood that drawing of the logs over the skids is rendered very difficult, very often resulting in 80 accidents, as by lateral or longitudinal slipping of the logs on the skids. By the use of the improved anti-skid chains C, and their incidental connecting parts, the skids B can be utilized to render a log piling operation 85 comparatively easy, under various circumstances.

Referring to the skids B, the same may be of any approved construction, ordinarily being the shape of specially cut timber, 90 having the upper ends thereof recessed as at 10 to conform to the curvature of a log 11, on the upper tier of the logs being piled. Generally, the skids B are tapered toward their lower ends 12, and especially at the 95 bottom surface 13 adjacent said lower ends 12.

Referring to the links B of the anti-skid chain C, each of said links is substantially U-shaped in formation, including leg or arm 100 portions 15 and 16, which are connected by a bight or transverse portion 17 at an end of each. The arms 15 and 16 are of peculiar formation, preferably having top and bottom flat surfaces 18 and 19 respectively. 105 These arms 15 and 16 are preferably polygonal in cross section and at their free ends are offset, so that the space intermediate the inside or facing edges of said arms 15 and 16 is relatively wide to permit the insertion 110

of the connecting portion 17 of the next adjacent link. The arms 15 and 16, moreover, are provided with the bulge or reinforcing portion 20, at the free ends thereof, preferably depending from the lower surface 19, which cooperates with the skid B in maintaining the links D in proper manner.

The top surfaces 18 of the link arms 15 and 16 are preferably provided with the upwardly extending conical shaped calks 25, which are preferably disposed in a reinforced portion substantially midway of the ends of each of said arms 15 and 16. On these top surfaces 18, the arms 15 and 16 are each preferably provided with the outwardly extending pyramidal shaped calks 26, which may be disposed adjacent the free ends of said arms, substantially as is illustrated in Figures 2 and 4 of the drawing. These calks 25 and 26 are thus arranged substantially at right angles to the plane defined by the link D, and are pointed so that the same may engage a log or other article, as will be subsequently mentioned. The lower surfaces 19 of the link arms 15 and 16 are each preferably provided with a pyramidal shaped calk 28, which extends substantially at right angles to the plane defined by the links on which they are positioned, the same extending directly opposite to the calks 25. It is preferred that the facing surfaces 30 of these calks 28 be substantially perpendicular to the plane defined by the links D or slightly canted, the purpose of such construction being that of prevention of lateral slipping of the links D, as the calks 28 are adapted for biting into the material of the skids B, as will be hereinafter mentioned. It is preferred that a pyramidal shaped calk 31 be provided, which extends substantially at right angles from the plane of each link D, and in the same direction as the skid engaging calks 28, said calk 31 being rigidly and integrally mounted upon the bight portion 17, substantially midway of the ends thereof.

Referring to the manner of connecting the links D to form the improved chain C, it is to be noted that each link D is provided with the relatively long transverse recess or passageway 35 which extends through the bight or connecting portion 17. The free ends of the arms 15 and 16 are likewise provided with the aligning transverse passageways 37. The connecting portion 17 of one link is adapted for assemblage in the space intermediate the arms 15 and 16 of an adjacent link, so that the passageway 35 of the connection 17 aligns with the passageways 37 of the arms 15 and 16 of said adjacent link. In this position, the adjacent links may be pivotally connected by means of a pin or pintle member 39, which may be riveted or detachably connected to effect the pivoting of said links D. In this manner, the chain C

may be constructed of any desired number of the links D, consistent with the length of the skid B.

Referring to the mounting of a chain C upon a skid B, it is preferred that a clevis 40 or yoke member be pivotally connected, as by a transverse pin 41, to the uppermost link D, as by insertion of said pin 41 through the passageway 35 of the uppermost link D. This yoke 40 is provided with an outwardly extending hook 44 which is provided with a pointed end 45. In the placing of the chain C upon the skid B, the hooked end 44, and particularly the pointed end 45 thereof, digs into the upper end surface of the skid B, so that the chain C is prevented from downward longitudinal movement along the skid B, as can be readily understood. In order to laterally reinforce and stabilize the upper end of the chain C, it is preferred to provide spike elements 47 upon each outwardly extending end of the pin 41, as by links or a chain element 48; said spikes 47 being adapted for driving engagement within the skid B or log A, and thus preventing any lateral movement of the yoke member 40.

The links D of the chain C are placed upon the skid B, and the calks 28 and 31 bite or engage, as by hammering, into the material of the skid B, so that each link D is fixedly connected to the skid B in a simple and effective manner, against liability of longitudinal or lateral displacement. To obviate any liability of displacement of the links D, a chain E has been provided, which is connected as by its upper link 50 through an aperture 51 in an end of the yoke 40. The chain E is spirally wrapped about the skid B and about the various links D, so that the link elements of the chain E engage over the conical shaped calks 25. It can thus be understood that by such spiral wrapping of the chain C, each link D is additionally secured to the skid B by reason of engagement of said chain E over the conical shaped calks 25. The lower end of the chain E may be wrapped or secured in any approved manner to the lower end of the skid B, as by fastening to lower pintle 39.

The skid B may, of course, be of any length, and the links D may be of any number consistent with the length of the skid B. In order to facilitate handling of the chain C, it is preferred that for a relatively long skid B, the chain C be made in sections and detachably connected, as by means of making certain of the pintle elements 39 detachable.

From the foregoing description of this invention, it can be seen that a relatively simple and compact anti-slipping chain for skids has been provided, which will withstand the rough handling and severe strains imposed upon the same incident to log piling.

It can readily be understood that the calks 25 and 26 will prevent any logs from sliding backward over the inclined skids B, and will thus prevent accident. Lateral as well as 5 longitudinal slipping of the logs is insured against. The improved chain C may be readily detached from one skid and assembled to another skid. It is also contemplated to make the various calk elements of 10 the links detachable since upon wearing out of said links it might be desirable to supply a new calk in lieu of entirely new links.

Various changes in the shape, size and arrangement of parts may be made to the form 15 of invention herein shown and described, without departing from the spirit of this invention or the scope of the claims.

I claim:

1. In a logging guideway, the combination 20 of a skid member, an anti-slip chain for said skid member, and means for attachment of said anti-slip chain to said skid member.

2. In a device of the class described, the combination of a skid member, an anti-slip chain including calk portions thereon, and means for detachably affixing said anti-slip 25 chain to said skid member.

3. As an article of manufacture, an anti-slip link having calks extending outwardly 30 from opposite sides thereof.

4. As an article of manufacture, an anti-slip link having calk members extending laterally on opposite sides of the plane defined by said link.

35 5. As an article of manufacture, an anti-slip link of substantially U-shape including arm portions and a connecting bar portion, said arm portions having calks extending outwardly of a side thereof.

40 6. As an article of manufacture, an anti-slip link including arm portions, and a connecting bar portion for said arm portions, of substantially U-shaped formation, said arm portions having calks extending outwardly 45 of the plane in which the same lie on opposite sides thereof.

7. As an article of manufacture, a link element for anti-slip chains of substantially U-shaped formation including arm portions 50 and a connecting portion rigidly affixed to an end of each of said arm portions to provide a substantially U-shaped structure, opposite sides of said arm portions being relatively flat and provided with pointed calk elements extended outwardly at right angles to the plane defined by said link arms and connecting portion, said connecting portion having a calk member extending outwardly to one side of said link.

60 8. As an article of manufacture, an anti-slip chain having pointed calks extending outwardly from opposite sides thereof.

9. In a device of the class described, the combination of a skid member, an anti-slip arrangement including a hooked member adapted for engagement over the upper end of said skid member so that the anti-slip arrangement extends longitudinally along the upper surface of said skid member, and means for spiking said anti-slip arrangement to said skid member throughout the length thereof. 65 70

10. In a device of the class described, the combination with a timber skid, of an anti-slip chain including a plurality of links having calks extending outwardly therefrom in opposite directions, the calks on one side of said anti-slip chain being adapted for biting into the timber skid so that the calks on the other side of said chain extend upwardly of said skid member, and hook means on the end of said anti-slip chain adapted for biting into the upper end of said skid member. 75 80

11. In a device of the class described, the combination of a timber skid, an anti-slip chain including a plurality of links each having calk elements extending outwardly from opposite sides thereof, the calks on one side of the chain being adapted for biting relation with the skid so that the calks on the other side extend outwardly of said skid, means on the upper end of said anti-slip chain fixedly secured to the upper end of said skid, and a chain member adapted for spiral winding about said anti-slip chain and said skid to engage certain calks which extend upwardly from said skid. 85 90 95

12. In combination with a timber skid, of an anti-slip chain formed of a plurality of pivotally connected substantially U-shaped links, each of said links having pointed calk members extending outwardly from opposite sides thereof, the calks extending from one side of said chain being adapted for biting relation into the material of said timber skid so that the calks on the other side of the chain extend outwardly of said skid, a yoke member pivotally connected to the upper end of said chain having a hook extending outwardly thereof adapted for biting engagement inwardly of the end surface of said skid to prevent downward longitudinal movement of the anti-slip chain upon said skid, means for affixing said yoke and the upper end of said chain against lateral movement upon said skid, and means wound about said skid and said chain engaging certain upstanding calks in the links of said chain and adapted for securing said chain against displacement from said skid. 100 105 110 115 120

ROBERT FRIEDELEY.
